UNITED STATES PATENT OFFICE.

CHARLES G. SHEPARD AND PETER ADAMS, JR., OF BUFFALO, NEW YORK.

DESIGN FOR A BLIND-HINGE.

SPECIFICATION forming part of Design No. 14,595, dated January 29, 1884.

Application filed November 23, 1883. Term of patent 7 years.

To all whom it may concern:

Be it known that we, CHARLES G. SHEPARD and PETER ADAMS, Jr., both of the city of Buffalo, in the county of Erie and State of New York, have invented and produced a new and original Design for Blind-Hinges, of which the following is a specification.

Our design relates to that class of blind-hinges which consist of two detachable portions, an eye portion and a pintle portion, each provided with a leaf or plate.

In the accompanying drawings, Figures 1, 2, and 3 represent elevations of blind-hinges differing slightly in form, but all embodying our new design.

Like letters of reference denote like parts in the several figures.

A represents the knuckle of the eye portion of the hinge, B the leaf of said portion, and C the shank. D represents the pintle, E the leaf of the pintle portion, and F the shank. The leaves B and E are rectangular in form and arranged with their longest side in an upright position. The leaves are provided with raised marginal ribs or beads b and e, respect-

ively, extending all around the leaves and the edges of the shanks C and F to the knuckles of the respective parts of the hinge. i represents the screw-holes formed in the leaves B and E, and surrounded by raised beads j. K represents a finial having the form of an acorn, and applied to the upper end of the pintle D. l is a similar ornament formed at the lower side of the shank F in the same vertical line with the pintle D.

35 We claim as our design—

In a design for a blind-hinge, the shape or configuration of the parts herein shown and described, the same consisting of upright elongated rectangular leaves B E, having raised marginal beads b e and screw-holes i, surrounded by raised beads j, the shanks C F, and finials k l, respectively.

40 Witness our hands this 20th day of November, 1883.

CHARLES G. SHEPARD.
PETER ADAMS, JR.

In presence of—

JNO. J. BONNER,
CHAS. F. GEYER.
